UNITED STATES PATENT OFFICE.

WILLIAM J. SULLIVAN, OF CHICAGO, ILLINOIS.

ARMOR FOR BASE-BALL PLAYERS.

932,352.

Specification of Letters Patent. Patented Aug. 24, 1909.

Application filed May 29, 1909. Serial No. 499,244.

To all whom it may concern:

Be it known that I, WILLIAM J. SULLIVAN, a citizen of the United States, residing at Chicago, in the county of Cook and State of Illinois, have invented new and useful Improvements in Armor for Base-Ball Players, 5 of which the following is a specification.

My invention relates to armor for base ball players, and pertains more particularly to 10 padded body protectors for base ball catchers.

The object of my invention is to provide a body protector that will more effectually resist the force of impact of a ball, and will 15 better conform to the contour of the body, thus avoiding displacement and interference with the free action of the wearer.

A further object thereof is to provide means for attachment of same to the body in 20 such manner that the face thereof slopes from the center backward on each side, thus deflecting the force of the impact of the ball.

A still further object of my invention is to 25 provide a protector comprising a main body portion composed of horizontally disposed padded pockets, and a depending portion loosely carried upon the main body portion composed of vertically disposed padded pockets.

Another object thereof, is to provide a longitudinal reinforcing tongue and laced closure 30 for the outer edge of the protector whereby the padded pockets may be closed but permitting the opening thereof for access 35 thereto to repair or replace the padding material.

To these ends my invention includes the combination and arrangement of component parts to be hereinafter described and more 40 particularly pointed out in the claims.

In the accompanying drawings illustrating 45 my invention, in which like reference characters indicate similar parts, Figure 1 is a front view thereof; Fig. 2 is a back view of the same; Fig. 3 is a longitudinal sectional view; Fig. 4 is a transverse sectional view of my invention; Fig. 5 is a detail sectional view of the outer edge of my protector, and Fig. 6 is a plan view of the blank for forming 50 loops for adjustably attaching the harness upon the protector.

My invention includes, generally, a body protector comprising a main body portion and shoulder extensions, a depending flap 55 upon the lower end of the main body portion, and suitable straps and fastenings

adapted to hold the main body portion snugly at the side of the wearer and the shoulder extensions upon his shoulders. The protector is formed of flexible front and back 60 pieces stitched in parallel seams to form pockets which are stuffed with suitable padding and stiffening material. The main body portion is divided into two sections by a medial vertical seam, and the pockets 65 therein are formed horizontally, and extend from the central seam to the outer edge of the protector. The depending flap is flexibly attached to the main body portion, and the pockets or quilting therein are arranged 70 vertically to impart stiffness thereto for the purposes hereinafter described.

Adjacent to the outer edge of the front and back section, a reinforcing tongue and row of eyelets are provided for lacing the sections 75 together and the reinforcing longitudinal strip or tongue is stitched to the back section adjacent to the outer edge to serve as a closure for the outer ends of the pockets in the protector and to stiffen the outer edge 80 thereof.

Referring now to the drawings, 1 designates the main body portion of my protector, and 2 indicates the extensions adapted to cover the shoulders of the wearer. As shown 85 in the drawings, said portions are formed of front and back pieces 3 and 4, respectively, of suitable flexible fabric, such as duck or canvas and shaped to cover the abdomen, chest and shoulders of the wearer. The said 90 pieces are stitched together by a medial vertical seam 5, and also stitched transversely to form a plurality of horizontal pockets 6, which are stuffed with suitable padding material 7. 95

Flexibly secured to the main body portion 1, I provide a depending portion 9, made of similar material as the main body portion, but provided with vertically arranged pockets, adapted to impart rigidity to the same, 100 and overcome the tendency of protectors to bend outwardly in use, and thus uncover the lower parts of the body which it is designed to protect.

The front and back pieces 3 and 4 are each 105 provided with a row of eyelets 10 and 11 adjacent to their outer edges by which they are laced together by the tie strings 12.

In a protector of the character described, 110 it is important that the upper and lower sections be retained in shape and position rigidly and at the same time be susceptible of

opening for the alteration or repair of the padding material. For this purpose, I provide a longitudinal tongue or strip 13 stitched to the outer edge of the back piece 4 and 5 laced therewith to the front piece 3. Said tongue projects inwardly and lies against the front piece 3 and thus forms a closure for the horizontal and vertical pockets and retains the padding therein. Said tongue may be 10 severed at 14 to accommodate the flexible joint between the upper and lower sections of the protector.

The harness for securing my protector in a protruding position upon the body comprises the upper and lower straps 15 and 16, 15 respectively, and the vertically adjustable medial strap 16, and back plate 17.

As shown in the drawing, the upper straps 15 are secured to the shoulder portions at 20 their upper ends 18 and are united to the medial strap 16 at the middle of the back of the wearer. Said medial strap is adjustably secured at the plate 17 by the buckle 19. The lower strap 16 is secured at one side of 25 the main body portion of the protector at 20 by the ring 23 and is passed through slits in the plate 17 and fastened to the opposite side of the protector by the snap-hook 21 and ring 22.

30 For the purpose of vertically adjusting the lower strap 16 upon the main body portion of the protector, I attach the rings 22 and 23 thereto by the loops 24, which, as shown, are provided with inner and outer eyelets 25 and 35 26, through which the loops are laced by the tie strings 12. By this construction, straps may also be readily and conveniently renewed in case of breakage.

Having thus described my invention, what 40 I claim as new and desire to secure by Letters Patent, is—

1. A body protector comprising a main body portion made of an inner and outer piece of flexible fabric united by a medial 45 longitudinal seam and stitched laterally forming pockets for padding materials, a depending portion flexibly attached to the main body portion made of like materials stitched longitudinally forming pockets for 50 padding materials, a longitudinal tongue stitched to the inner piece of fabric adjacent to its outer edge adapted to lie against the inner face of the outer piece and form a closure for the pockets of padding materials,

and a row of eyelets on each of said pieces adjacent to their outer edges, and tie strings adapted to lace the same together, substantially as described. 55

2. A body protector comprising an inner and outer piece of flexible fabric suitably 60 stitched together to form pockets for padding materials, a longitudinal tongue stitched to one of said pieces adjacent to its outer edge adapted to lie against the inner face of the opposite piece, and a row of eyelets on each of said pieces adjacent to their outer edges, and tie strings adapted to lace the same together, substantially as described. 65

3. A body protector comprising an inner and outer piece of flexible fabric suitably 70 stitched to form pockets for padding materials, formed into a main body portion and shoulder extensions having a medial longitudinal joint and a vertically depending portion, a longitudinal tongue stitched to one of said pieces adjacent to its outer edge adapted to lie against the inner face of the opposite piece, a row of eyelets on each of said pieces adjacent to their outer edges, tie strings 75 adapted to lace the same together, upper and lower fastening straps adjustably connected through a plate and medial strap at the back of the wearer, whereby the shoulder extensions and side edges of the body portion are 80 held against the body and the front of the protector in a buckled and protruding position upon its medial horizontal joint, substantially as described. 85

4. A body protector comprising an inner and outer piece of flexible fabric stitched together to form pockets for padding material, a row of eyelets on the inner and outer pieces adjacent to their outer edges, tie strings 90 adapted to lace the same together, adjustable straps adapted to secure the protector upon the body of the wearer, and loops for attaching said straps to the protector adapted to be laced by said tie strings to the protector, substantially as described. 95

In testimony whereof, I have hereunto signed my name to this specification in the presence of two subscribing witnesses. 100

WILLIAM J. SULLIVAN.
